UNITED STATES PATENT OFFICE.

WILLIAM H. GAULKE, OF MILWAUKEE, WISCONSIN, ASSIGNOR TO INDEPENDENT ELECTRIC MANUFACTURING CO., OF MILWAUKEE, WISCONSIN.

CONTROLLING DEVICE.

1,070,597.

Specification of Letters Patent. Patented Aug. 19, 1913.

Application filed August 12, 1912. Serial No. 714,714.

To all whom it may concern:

Be it known that I, WILLIAM H. GAULKE, a citizen of the United States, residing at Milwaukee, in the county of Milwaukee and State of Wisconsin, have invented a certain new and useful Improvement in Controlling Devices, of which the following is a full, clear, concise, and exact description, reference being had to the accompanying drawings, forming a part of this specification.

My invention relates to controlling devices and more particularly to alternating current starting devices in the general nature of rheostat starting devices.

My invention is more particularly an improvement over the device disclosed in my Patent No. 1,009,661, issued Nov. 21, 1911. I find that in devices of this general character in which a magnet is used to hold a switch arm, a specially constructed magnet which may retain its armature in an attracted position under the influence of alternating currents is required and my said patent discloses an electromagnet of this general character. This electromagnet is designed by means of its armature to hold in a limiting position the rheostat switch arm. This switch arm is spring controlled and strong tendency exists to restore this arm to its normal position, which tendency must be overcome due to the action of the magnet so long as alternating current traverses its winding. The tractive effort of this electromagnet, however, is not very large and I find that a special construction of mechanism interposed between the magnet armature and the switch arm is desirable in order that the means tending to restore the switch arm to normal position will be ineffective so long as alternating current is present in the magnet winding. To this end my invention herein is particularly directed.

I will explain one embodiment of my invention in connection with the accompanying drawing, this embodiment setting forth one of the ways in which I have used my invention to accomplish the desired result. In this drawing I represent the front plate of a rheostat starting device with the apparatus normally mounted on the front face of this front plate. In this illustration the front plate 1 is designed to cover a box-like structure mounted to the rear of this plate to which this front plate is secured by means of screws 2, 2. This box-like structure is

not shown as it forms no part of the invention, being merely for the purpose of holding the resistance units which are adapted for connection with contact segments 3, 3. A switch arm 4 pivoted at 5 and having a handle 6 is designed to coöperate with the segments 3 and also carries a contact element 7 designed to coöperate with contacts 8 and 9. This switch arm carries a lug or pin 10 by means of which it is finally held in its limiting position as will be apparent hereinafter.

An electromagnet 11 is mounted to the plate 1 and is similar in its general characteristics to the electromagnet set forth in my said patent. This electromagnet by means of its terminals 12, 12 is designed to control an armature 13 having a core piece 14. As this device is used for alternating currents the electromagnet 11 must retain its armature 13 in an attracted position under the influence of alternating current. For this reason the special construction set forth in my said patent is utilized.

As the effort exerted by the magnet 11 against the armature is rather slight during the reversal of the polarity of the current, I desire a holding arrangement for the switch arm 4 which will not normally tend to restore the armature 13 to its unattracted position with any very great effort. To this end I use a bar 15 pivoted at 16 which has an inclined surface 17. This bar 15 also has a notch 18. Now when the arm 4 is moved into its limiting position the pin 10 engages the surface 17 temporarily to lift the bar 15 upwardly until the pin 10 engages the notch 18, in which position the arm 4 is then held provided the armature 13 is attracted as this armature 13 bears by means of a resilient arm 19 against the right hand extremity of the bar 15. Limit stops 20 and 21 are provided for the bar 15. It will thus be seen that the spring 22 which normally tends to restore the arm 4 against its stop 23 will exert its pull against the bar 15 with no tendency to restore the armature 13 to normal. A slight tendency to restore this armature 13 to its unattracted position is due to the over-weighted construction of the bar 15, but this tendency is very slight and not sufficient to restore this armature when alternating current traverses the winding of the magnet 11. Should the circuit through the magnet 11 be broken, however, the armature 11

moves into the position shown in the illustration and the over-weighted bar 15 also moves into the position shown in the illustration whereupon the spring 22 can restore 5 the arm 4 to normal.

While I have herein shown and particularly described one form of carrying out my invention, I do not mean to limit myself to such specific embodiment, but—

10 Having thus described and shown one form of my invention, what I claim as new and desire to secure by Letters Patent is:

1. In a device of the character described the combination with a contact arm, means 15 tending to move said arm in a given direction, and means to hold said arm in a given position in opposition to said first aforesaid means, said last aforesaid means comprising an electromagnet adapted to be 20 energized by alternating currents, an armature therefor, an overweighted arm under the control of said armature, a spring on said armature for engaging said arm, and means on said contact arm adapted to engage 25 said arm and be held thereby, the engagement between said last aforesaid means and said overweighted arm being against a surface substantially parallel to the direction of motion of said overweighted arm.

30 2. In a device of the character described the combination with a contact arm, means tending to move said arm in a given direction, and means to hold said arm in a given position in opposition to said first aforesaid 35 means, said last aforesaid means comprising an electromagnet adapted to be energized by alternating currents, an armature therefor, an overweighted arm under the control of said armature, a spring on 40 said armature for engaging said arm, a pin on said contact arm adapted to engage said arm and be held thereby, and a notch in said arm with which said pin co-operates, the engagement between said last aforesaid 45 means and said overweighted arm being against a surface substantially parallel to the direction of motion of said overweighted arm.

3. In a device of the character described, 50 the combination with a contact arm, means tending to move said arm in a given direction, and means to hold said arm in a given position in opposition to said first aforesaid means, said last aforesaid means comprising 55 an electromagnet adapted to be energized by alternating currents, an armature therefor, a pivotally mounted arm under the control of said armature, a spring on said armature for engaging said arm, and means

on said contact arm adapted to engage said 60 arm and be held thereby, said means tending to restore the contact arm exerting its effort against said pivotal mounting.

4. In a device of the character described the combination with a contact arm, means 65 tending to move said arm in a given direction, and means to hold said arm in a given position in opposition to said first aforesaid means, said last aforesaid means comprising an electromagnet adapted to be energized 70 by alternating currents, an armature therefor, a pivotally mounted arm under the control of said armature, a spring on said armature for engaging said arm, a pin on said contact arm adapted to engage said arm and 75 be held thereby, and a notch in said arm with which said pin co-operates, said means tending to restore the contact arm exerting its effort against said pivotal mounting.

5. In a device of the character described 80 the combination with a contact arm, means tending to move said arm in a given direction, and means to hold said arm in a given position in opposition to said first aforesaid means, said last aforesaid means comprising 85 an electromagnet adapted to be energized by alternating currents, an armature therefor, an overweighted pivotally mounted arm under the control of said armature, a spring on said armature for engaging said arm, and means on said contact arm adapted to engage 90 said arm and be held thereby, said means tending to restore the contact arm exerting its effort against said pivotal mounting.

6. In a device of the character described the combination with a contact arm, means tending to move said arm in a given direction, and means to hold said arm in a given position in opposition to said first aforesaid 100 means, said last aforesaid means comprising an electromagnet adapted to be energized by alternating currents, an armature therefor, an overweighted pivotally mounted arm under the control of said armature, a spring 105 on said armature for engaging said arm, a pin on said contact arm adapted to engage said arm and be held thereby, and a notch in said arm with which said pin co-operates, said means tending to restore the contact arm 110 exerting its effort against said pivotal mounting.

In witness whereof, I hereunto subscribe my name this 12th day of July A. D., 1912.

WILLIAM H. GAULKE.
